UNITED STATES PATENT OFFICE.

JOSEPH H. BAIR, OF PHILADELPHIA, PENNSYLVANIA.

TICKET-PRINTING MACHINE.

1,083,267.

Specification of Letters Patent.

Patented Jan. 6, 1914.

Application filed September 7, 1912. Serial No. 719,100.

To all whom it may concern:

Be it known that I, JOSEPH H. BAIR, a citizen of the United States of America, and a resident of Philadelphia, county of Philadelphia, Pennsylvania, have invented certain new and useful Improvements in Ticket-Printing Machines, of which the following is a specification.

This invention relates to ticket printing machines for use in printing tickets of the customary size and material either for transportation between two given points over land or by water, or for admission to places of amusement or the like, such as base ball games, for instance. Such tickets are usually made of cardboard and of a convenient size for handling.

The invention will be more fully understood from the following specification and the accompanying drawings in which—

Figure 1 is a transverse sectional view of a machine embodying my invention. Fig. 2 is a plan view of the machine, partly in section and with parts omitted. Fig. 3 is a front elevation of the machine. Fig. 4 is a right hand end view. Figs. 5, 6 and 7 are detail views of the ticket plate feeders which carry the ticket plates from the plate wheels to the form. Fig. 8 illustrates one form of form surface and ticket plate for printing tickets from one place to another, and Figs. 9 to 12 illustrate the four selective platen surfaces for printing different kinds of tickets from the one plate.

Referring to the drawing, 1 designates a base which may contain a cash drawer 2 if desired, and on which are mounted two side frames 3, 3 in which is journaled a shaft 4. On the latter is secured a plate wheel comprising three wheels, 5, 5, and 6. The outer wheels 5 have slots 7 and the center wheel 6 has slots 8. The plates 9 from which the tickets are printed are inserted in the slots as shown in Fig. 1 and held there by a snug fit. In the art of printing the plates 9 become the form members in the machine. The plate wheel as a whole may be rotated by means of the knob 10.

11 is a number disk fast on the shaft and provided on its periphery with as many numbers in sequence as there are plates carried by the wheel. A cover 12 fits over the number disk and is provided with an opening 13, see Fig. 3, through which the said numbers may be observed and any one of them placed in registry with a mark 14 for the purpose of placing a particular plate in

position to be used as will hereinafter appear. A toothed portion 15 of the wheel 11, having as many teeth as there are slots in 60 the plate wheel, coöperates with a pawl 16 to insure an exact positioning of the plate to be used, as will be understood, see Fig. 4.

17 is a form carrier suitably supported on the base 1 and having a slot 18 in which 65 there is inserted a "date" block 19 for printing the date on the ticket. The form carrier is further provided with fixed type forms for printing special indicia such as "half" to indicate a half fare as the case may 70 be and as will hereinafter be more fully referred to.

20 is a platen having means for selective printing of the ticket, that is to say, each of the four surfaces of the platen are provided 75 with contact or printing faces whereby only certain of the indicia carried by the form will be printed as may be wanted in a particular instance. This will also be explained more fully in connection with the 80 operation of the machine. The platen 20 is rotatably mounted in the sides 21, 21 of the cover 22. This latter forms a lever, so to speak, for the operation of the platen with a fulcrum on the shaft 4. In the center the 85 cover is provided with teeth 23 with which meshes the gear 24 centrally carried by a sleeve 60 on the operating shaft 25. The latter is journaled in the fixed side frames 3 of the machine and is provided with a 90 handle 26, which has a shoulder 61 adapted to engage a shoulder 62 on the sleeve, see Fig. 3, to obtain a free motion between the shaft and the sleeve in a well known manner. At the one end the journal of the platen 95 carries a wheel 27 having four notches 28. 29 is a spring pawl adapted to enter said notches. When a particular form of ticket is wanted, the platen is rotated until the selected surface thereof is downward. At 100 the right moment the pawl 29 snaps into a notch 28 to retain the platen in position.

30 represents the tickets of stiff cardboard and which are contained in a suitable ticket holder of a size corresponding to the amount 105 of the business to be expected at a particular office.

32 is a weight to keep the tickets down in the holder which latter is open as at 33 to facilitate handling and insertion of the 110 tickets.

When in the holder the tickets rest on the two side shelves 34, 34 which have grooves or ways 35 and which extend rear-

wardly to support also the ticket which is to be printed and as shown in Fig. 2. Outside the ticket holder the shelves 34 may have guides 35. Thus there is provided an open space beneath the tickets and in the center between the shelves 34. In this space and guided in the said guides 35 moves a ticket feeder 37 which has a shoulder 38 to push the lowermost ticket out from under the pile.

39 is a rack secured to the ticket feeder. 40 is a gear which meshes with said rack 39 and which is fast on a shaft 41 journaled in the side frames. At both ends of said shaft there is a gear 42 in mesh with a toothed segment 43 carried by a rock-shaft 44 journaled in the side frames.

45, 46 are thin flat but stiff wires fast in the ticket feeder 37. Said wires being bent outward and then rearward as shown, the rearward ends forming loops or hooks 46 which overlap the corner of the ticket which is to be printed. Besides serving to eject the printed ticket, the wire loops 46 protect the front edge of the ticket when the latter is fed onto the form under the ribbon.

47 is a depending arm from the shaft 25 which engages one of the segments 42, Fig. 1.

48 is a typewriter or similar ribbon which runs over the form and down on each side over spools 49, only one of which is shown in Fig. 1.

I propose to use any convenient form of ribbon shifter device to move the ribbon lengthwise over the form in an obvious manner.

The ticket plates are removed from the wheel and placed in position to print by the following means. See Figs. 5 to 7. The device is alike for both ends of the ticket so only one will be described. 50 is a guide block fast on the side frame 3 and on which slides a block slide 51. Pivoted on the latter are the link 52 and the cam piece 53. Pivoted to the end of the latter are the plate feeders 54 having a V-shaped nose 55 adapted to enter a V-notch 56 in the end of the plate. 57 is a post in the cam block. 58 is a link connecting the slide 51 with the toothed segment 43. When the latter is moved forwardly, the slide is operated in the same direction, and as it moves the cam piece 53 is pulled around the post to cause the plate feeder to move inwardly so that the nose 55 will enter the notch 56, whereby the plate will be seized at each end and carried forward in over the form under the ribbon ready to print. On the return movement the plate is first pushed into the notches in the plate wheel and thereafter the feeders 54 are moved sidewise into retracted position. Figs. 5 and 6 clearly illustrate this operation.

Before being placed in the ticket holder the tickets will be printed with the name of

the transportation company and general transportation clauses and the like. But the points of destination, the price and the nature of the fare will not be printed thereon. These items are printed by my machine as the tickets are sold and consequently the ticket plates are stamped or otherwise formed so as to print these items.

Assuming that a ticket is wanted. The operator first rotates the plate wheel until the number of the plate to be used registers with the mark 14 and observed through the opening 13. As already explained the toothed wheel portion 15 and the pawl 16 insures proper positioning of the plate wanted. Thereafter the handle 26 is moved quickly downward. The first part of this downward movement operates the toothed segments 43 through the instrumentality of the depending arm 47 and the ticket resting outside the ticket holder is pushed in over the form above the ribbon, and at the same time, the plate wanted is moved out from the plate wheel and in under the ribbon by the plate feeders 54. The parts are so timed that immediately thereafter the shoulder 61 on the handle 26 abuts the shoulder 62 on the sleeve 60 thereby rotating the latter and the gear 24 which in turn causes a downward movement, in the nature of a blow, by the cover 22 and the platen 20, and as a consequence thereof, the typed matter on the date block, the form and the ticket plate will be printed on the ticket. The handle 26 is returned to its normal position by a spring 65 until it abuts a stop 66, Fig. 4, and at the same time the segments 43 are returned to the position shown in Fig. 1 by springs 67 which force them against stops 68. On the return stroke, to the left in Fig. 1, the hooks or loops 46 serve to eject the printed ticket into the receptacle 69, the printed ticket passing out between the rear edge of the next ticket to be printed and the front edge of the form which latter for this purpose is slightly lower than the level of the lowermost ticket. From this it will be seen that by one operation of the handle 26, the ticket is fed onto the form from the one side, the ticket plate is fed from the opposite side, the ticket is printed and thereafter ejected and the parts are put into position for a new operation.

It should be noted that one feature of my invention relates to the system or manner for printing different kinds of tickets from one plate for use between two stations. Referring to Fig. 8 it will be seen that the plate 9 for tickets between Boston and New York, for instance, has formed thereon the names of the places of destination, the full and half fare and the words "To" and "From." Figs. 9 to 12 illustrate the four different printing surfaces on the platen for printing either a full or a half fare one way

ticket; or a full or a half fare return trip ticket. For the purpose of clearness, Fig. 8 is lettered right side up. In reality the types are upside down. In Fig. 9 the printing surface is shaded, so that if the surface 80 of the platen 20 is lowermost a full fare one way ticket is printed because the portions of the printing surface which corresponds to the "Half," the "stub" and 10 "From" are cut away, consequently will not print. Fig. 10 illustrates the half fare one way platen printing surface 81 which prints everything but the "From" and the stub and the full fare. Fig. 11 illustrates 15 the full fare return ticket platen surface 82 which prints everything but the "To," "Half" and the half fare. Fig. 12 illustrates the half fare return ticket platen surface 83 which prints everything but the 20 "To" and the full fare prices. Thus one plate serves for printing the four kinds of tickets between New York and Boston or any other two places by the use of the four selective surfaces on the platen.

25 In order to facilitate the turning of the platen, the latter may be provided at its one end and outside the casing with a suitable knob or handle 83, Fig. 3, provided with marks to indicate the positions of each of 30 the four selective surfaces.

The plate illustrated in Fig. 8 embodies only one of the many variations of plates which it may be desired to use and it is one of the advantages of this method of printing tickets that it is adaptable for several purposes. For instance, the price may be omitted on that half of the ticket, which is given to the purchaser and printed on the other half for auditing purposes and as a 40 check upon the cash transactions in the ticket office. It will also be clear that only such tickets are printed as are actually needed, whereby a great saving is effected both as to the printing and handling of tickets 45 as well as in the auditing and keeping of accounts. Still another feature to be noted is that for special excursions and the like, a special plate may be provided and inserted in the machine.

50 I claim:

1. In a ticket printing machine the combination of a platen having selective impression surfaces, a stationary form carrier supported beneath said platen, a plurality 55 of ticket plates having printing characters for printing tickets therefrom, a common support for said ticket plates, means for moving any one of the said ticket plates away from said support and placing it upon the said form carrier and for moving the 60 said ticket plate away from said form carrier and placing it back into the said common support and means for operating the platen

to print selected portions from said ticket plate on a ticket. 65

2. In a ticket printing machine the combination of a platen having selective impression surfaces, means for rotating the platen to bring any one of the said impression surfaces into printing position, locking 70 means for said platen, a plurality of ticket plates having printing characters for printing tickets therefrom, supporting means for said ticket plates, means for moving any one of the said ticket plates away from the 75 said supporting means and placing it beneath said platen in printing position and for moving said ticket plate away from printing position and placing it back into the said supporting means and mechanism 80 for operating the said platen to print selected portions of the said ticket plate on a ticket.

3. In a ticket printing machine the combination of a frame, a shaft journaled therein, a plurality of ticket plates having printing characters for printing tickets therefrom, plate wheels secured to said shaft and provided with radial slots for the reception of the said ticket plates, a casing mounted 90 on said shaft, a platen having selective printing surfaces mounted in said casing, means for rotating the platen to bring any one of the said printing surfaces into printing position and mechanism for moving any 95 one of said ticket plates radially from said plate wheels into printing position under the platen, for operating said casing to bring the platen down to print a selected portion of the said ticket plate on a ticket, 100 for moving the said ticket plate back into its slots on the plate wheels and for returning the said platen and casing to starting position.

4. In a ticket printing machine the combination of a frame, ticket plates supported in the same, a casing journaled on said frame, a platen in said casing provided with selective impression surfaces, a support for a supply of tickets, a form carrier, means 110 for removing a ticket and placing the same on said form carrier, means for placing a ticket plate on the latter below said ticket, an operating shaft, and operating connections between the said shaft and the said 115 ticket and ticket plate operating means and the said casing for actuating the said operating means and for oscillating said casing to cause the platen to print a selected portion of said ticket plate on said ticket. 120

Signed at Philadelphia this third day of September 1912.

JOSEPH H. BAIR.
